United States Patent Office.

J. C. THOMPSON, OF CHARLESTOWN, ASSIGNOR TO HIMSELF AND JOHN H. ROGERS, OF BOSTON, MASSACHUSETTS.

Letters Patent No. 96,286, dated October 26, 1869.

IMPROVEMENT IN HOSE AND PIPE-COUPINGS.

The Schedule referred to in these Letters Patent and making part of the same.

To all whom it may concern:

Be it known that I, J. C. THOMPSON, of Charlestown, in the county of Middlesex, and State of Massachusetts, have invented an Improvement in Securing Hose to Couplings; and I do hereby declare that the following, taken in connection with the drawings which accompany and form part of this specification, is a description of my invention, sufficient to enable those skilled in the art to practise it.

Hose are often and commonly united to the neck-pieces of hose-couplings, especially the smaller kinds of hose known as hand-hose, and used for washing buildings, windows, sidewalks, &c., by winding their ends upon the coupling-necks with wire, preferably of copper.

This operation consumes some time, and the wire is very liable to break, by reason of the tensile strain put upon it, which strain is necessary to secure the hose upon the coupling-necks water-tight, and so as to prevent the coupling-necks from drawing out of the hose in actual use.

Moreover, the ends of the wire are apt to project and cut and scratch the hands and floors or other surfaces over which the hose are drawn in use.

My invention dispenses with the use of binding-wire; and

It consists in making use of a ring or ferrule upon the hose in the following manner:

A thin metallic ring or ferrule, the width of which approximates about one-third of its diameter, is placed over the end of the hose to be united to a coupling-neck, the outer diameter of the ring being about equal to or slightly less than the outer diameter of the hose. This compresses the hose, as seen in

Figure 1, which is a central longitudinal section through the end of a piece of hose, as it appears after the ferrule or ring is applied thereto. Then the hose is placed in a vise or clamp, leaving its end projecting beyond the distance which the coupling-neck is to fill therein.

Figure 2 is a view, partly in elevation and partly in longitudinal central section, showing the end of a piece of hose united to the neck of one part of the screw-coupling.

a is the hose;
b, the ferrule or ring thereon;
c, the coupling-neck; and
d, the nut-part of the coupling.

When the hose-end is secured in a vise or clamp, as stated, its inside surface is coated with rubber cement, and the outer grooved or ribbed surface of the coupling-neck *c* is also coated with rubber cement, and the end of *c* being entered in the open mouth of the hose, is driven home therein by a quick, powerful movement, expanding and stretching the material of the hose, and pinching it between the inner surface of ring *b* and the outer surface of *c*, to an extent which suffices to make a joint water or steam-tight under all pressures which the hose will bear, and which will effectually resist any strain likely to be exerted in practical use, tending to draw the coupling-neck out of the hose-end.

The use of the ring or ferrule *b*, as described, is especially adapted for rubber hose, though it may be applied to hose of other yielding material.

Other cementitious matter than rubber cement may be used, or cement may be omitted, though the best results are obtained by employment of cement.

The cement acts as a lubricant to facilitate entrance of the coupling-neck, and when cement is not used, the inside of the hose or the outside of the coupling-neck, or both, may be simply moistened or wet, to facilitate the entrance of the coupling-neck.

I claim the combination of the hose *a* with the coupling-neck *c*, by means of the ring *b*, applied and operating substantially as described.

J. C. THOMPSON.
